Atty.

UNITED STATES PATENT OFFICE.

WILLIAM A. FREEMAN, OF HAMILTON, ONTARIO, CANADA, ASSIGNOR TO W. A. FREEMAN COMPANY, LIMITED, OF HAMILTON, ONTARIO, CANADA.

REFRIGERATED DISPLAY-COUNTER TOP.

1,286,984.

Specification of Letters Patent.

Patented Dec. 10, 1918.

Application filed July 8, 1918. Serial No. 243,991.

To all whom it may concern:

Be it known that I, WILLIAM A. FREEMAN, a subject of the King of Great Britain, residing at Hamilton, in the county of Wentworth and Province of Ontario, Canada, have invented certain new and useful Improvements in Refrigerated Display-Counter Tops, of which the following is a specification.

10 My invention relates to refrigerated display counter tops, and consists essentially of a forwardly sloping or inclined counter top slab mounted upon a counter base, and display glass brackets superimposed upon 15 said slab, said brackets being of a design to support the front glass in a rearwardly inclined manner, and the top glass in a level manner, and refrigerating coils located in the transverse center of the counter in proximity to the level top glass.

The invention has for its object to provide means for securing clear vision of the whole counter top slab, both from the customer's side of the counter, and from the 25 butcher's or salesman's side, eliminating the necessity of stooping or leaning over the counter.

Another object is to provide means whereby is afforded a better perspective of the 30 perishable goods displayed upon the counter top slab.

A further object is to eliminate the old style coil box from the rear of the counter, which interfered with access to the counter 35 slab.

A still further object is attained by rendering the level top glass adapted for the display of non-perishable goods, by not requiring the same for vision of the counter 40 slab.

These, together with other objects are attained by the construction, combination and arrangement of the parts as will be hereinafter more fully described, illustrated 45 in the accompanying drawing, and pointed out in the claims hereunto appended.

Reference being had to the drawing, the figure indicates an end view of the refrigerated display counter, which illustrates the 50 invention to the best advantage.

A indicates the counter base, and B the counter top slab which usually consists of vitrilite or like material. This slab slopes forward, as portrayed in the figure.

55 C is the front and top glass holding

bracket, D the front glass which is inclined toward the rear of the counter, and E is the level top glass.

The slope of the slab B, combined with the proportions of the front glass C, permit 60 the customer's range of vision, as indicated by line 2, calculated from the average height of the eye from the floor, viz: five feet and four inches, the person standing at a distance of six inches from the front of the 65 counter, as indicated by line 3, to include the entire width of said slab.

The rear of the counter slab B is at substantially the average height of a counter slab from the floor. It is, then, to be understood that it is the front of the slab which is depressed from that height, and not the rear which is raised above that height.

The refrigerating coils F are situated at about half way back from the front of the 75 counter, and elevated to a point at which they will not interfere with the clear vision of the customer. The said coils may be suspended from the upper portion of bracket C, as illustrated, or supported in any other 80 practicable manner, at the option of the manufacturer.

The top glass E, not being required for vision of the slab B, as heretofore may be utilized for the display of nonperishable 85 goods, which, in addition, tends to shield the coils F from the sight of the customer.

The above described arrangement also permits the salesman's range of vision, as indicated by line 4, calculated from the 90 average height of the eye from the floor, standing close to the counter, as indicated by line 5; to include the entire width of the counter. The arrangement as shown permits the use of wide counter top slabs essential in most meat market conditions, the former method being to use a narrower slab, together with inclosed coil compartment in the rear of the slab, which necessitates the salesman's leaning or stooping over the 95 counter.

The sloping counter slab affords the necessary tendency for the down current of cold air to work forward to the front of the counter over the display of goods, and to 105 rise as it warms to be recirculated through the coils. If the counter slab was level, a rear vertical section rising to at least one quarter of the height of the front glass would be necessary to maintain even mod- 110

erate temperature over the displayed goods. It is desired to eliminate all obstructions upon the top of the slab.

The tendency of cold or cooling air to flow down even a slight slope is very marked, and very readily displaces any warm air until it in itself becomes warm.

Having now fully described my invention, what I claim and desire to secure by Letters Patent of the United States, is:—

- 10 1. In a counter of the class described, the combination with the counter base, of a counter top slab supported by the base and disposed in a position sloping forward, brackets extending upward and transverse of the counter top slab, front and top glass panels carried by said brackets, refrigeration coils disposed longitudinally of the counter top slab midway between the front and rear and at a sufficient height from the

counter top slab not to obstruct the view thereof from either side of the counter.

2. In a counter of the class described, the combination with the counter base, of a counter top slab supported by the base and disposed in a position sloping forward, front brackets extending upward and transverse of the counter top slab front and top glass panels carried by said brackets, said counter top slab, together with said glass panels 25 being proportionately arranged so as to permit unobstructed vision of the entire slab from either side of the counter, the lines of vision passing beneath the top glass panels, substantially as set forth and described. 30

In testimony whereof I have affixed my signature.

WILLIAM A. FREEMAN.
